JAIL CONSTRUCTION

Filed Jan. 8, 1931

UNITED STATES PATENT OFFICE

HARRY D. GARBER, OF CUYAHOGA FALLS, OHIO, ASSIGNOR TO THE VAN DORN IRON WORKS COMPANY, OF CLEVELAND, OHIO, A CORPORATION OF OHIO

JAIL CONSTRUCTION

Application filed January 8, 1931. Serial No. 507,418.

This invention relates to jail structures wherein a plurality of walls having sliding doors are so related that the doors move in different planes which planes may be parallel or angularly related. It is desirable that the movement and locking of jail doors be controlled from a common point and an improved apparatus for the purpose is illustrated and described in my copending application, Serial No. 507,417, filed January 8, 1931. Said application illustrates the system there shown as applied to a plurality of doors located in a common wall and therefore to move in a common plane. Such system includes a plurality of gap nuts one for each door, all the gap nuts being carried by a pull bar under operator control. Each door has a latch bolt engageable with or disengageable from its gap nut under individual operator control so that any or all doors may be caused to follow the pull bar opening and closing movement. Such a system of door control is broadly old and well-known in the art.

It is the object of the present invention to apply such system to doors moving in different planes, that is, to sliding doors located upon angularly related walls.

Another object of the invention is to supply such a system to the doors of spaced walls which may be parallel, by means rigidly interconnecting the pull bars of the two spaced walls yet not extending therebeyond. That is, the means of the present invention are arranged entirely between the two parallel walls the doors of which are to be connected. This object is accomplished by employing for the purpose endless means such as a chain bent about sprockets as will appear.

The exact nature of the invention together with further objects and advantages thereof will be apparent from the following description taken in connection with the accompanying drawings, in which Fig. 1 is a horizontal section through a pertinent portion of a jail installation showing the parts thereof interrelated according to my invention; and Fig. 2 is a detail in elevation of certain parts appearing in Fig. 1.

With reference now to the drawings, 1 and 2 represent parallel walls and 3 a wall ex-

tending transversely therebetween. These walls being part of jail structure, are barred as indicated. The walls 1 and 2 are of some substantial extent, and have a number of partition walls 4 extending therefrom to define cells as indicated. Cell No. I may be in front of the transverse walls 3 and the other cells therebehind; so that, with the exception of cell No. I the described wall structure defines a prisoners' corridor with a row of cells on either side thereof. In the parallel walls 1 and 2 which are cell front walls there is an opening for each cell, all of these openings leading each from its cell into the space between the cell rows. The cell front wall 2 may be carried beyond the transverse wall 3, and a wall 5 extended therefrom to the front corner of cell No. I, so that this latter cell opens into the safety vestibule provided by the wall 5, and in front of the wall 3. All of the other cell openings lead into the prisoners' corridor behind the wall 3. The wall 3 also has an opening connecting the safety vestibule with the prisoners' corridor.

For each of these openings there is provided a sliding door each movable along the wall in which its opening is located. Thus the door 6 is indicated for the opening 7 of cell No. I, and the door 8 is indicated for the opening 9 of the wall 3, the door 6 being in open position and the door 8 in closed position.

For operating the doors of the cell front wall 1, as more particularly shown in my copending application to which reference has been made, a pull bar 10 is provided extending along the length of the wall 1 and mounted for endwise movement therealong. This pull bar movement is controlled by operator-operated means located in the box 11 which is accessible outside of the safety vestibule; details of the mechanism for the purpose being immaterial here. For each door of its wall the pull bar is provided with a gap nut 12. Each door carries a latch bolt 13. Each latch bolt is movable on its door to engage or clear its gap nut 12, and is under operator control from the box 11 for this purpose. The range of motion of the pull bar 10 is of course, that of the doors of the

wall 1. Thus if all doors are connected with the pull bar, by engagement of their latch bolts with their respective gap nuts, all of the doors may be opened or closed from the box 11.

Such door operating arrangement is generally old and well known in the art.

In order that the door 8 of the transverse wall 3 may be likewise opened and closed this door also is provided with a latch bolt 14, and a gap nut 15 is provided therefor. This gap nut 15 is mounted on endless means which may include the pull rods 16 and which includes flexible elements such as the chains 17. The endless means is positioned so that its stretches extend and move along the wall 3, and to this end a pair of sprockets 18 are arranged at the ends of the wall and the chain sections 17 bent thereabout. It will be apparent that the gap nut 15 will thus move along the wall 3 to correspondingly move the door 8 when its latch bolt 14 is engaged.

If the sprocket 18 be positively driven by the pull rod 10 it will be apparent that the gap nut 15 of the wall 3 may have motion corresponding with the gap nut 12 of the wall 1. To this end a rack 19 is provided on the pull bar 10. An idler gear 20 is arranged to mesh with the rack 19 to drive the gear 21. This gear 21 is rigidly associated with the sprocket 18. The proportion and arrangement of the parts is such that travel of the gap nuts 12 and 15 will be coextensive; and, in Fig. 1 of the drawings, when the gap nut 12 moves to the right the gap nut 15 will move downwardly, both gap nuts thus moving in door-opening direction. Obviously, were it desired that the gap nut 15 travel in the opposite direction, by omission of the idler gear 20 and intermeshing of the gear 21 directly with the rack 19 this could be accomplished.

A pull bar 22 is arranged to control the doors of the wall 2 in exactly the same manner as the pull bar 10 controls those of the wall 1. That the pull bar 22 may have motion with the pull bar 10, a rack 23 is provided on the pull bar 22 and a gear 24 meshing with the rack is rigidly associated with the corresponding sprocket 18. Obviously by this arrangement the pull bars 10 and 22 will have coextensive parallel motion in the same direction, that is, they will move with each other as to both distance and direction.

Of course, were the idler gear 20 omitted as above described the pull bar 22 could be caused to move the same distance but in the opposite direction from the pull bar 10. It will be noted that by the described arrangement positive interconnection is had between the gap nuts of the three walls by means not requiring clearance space beyond either of the two parallel walls.

What I claim is:

1. In a jail structure having a pair of cell rows with a corridor therebetween, the front walls of said cells having door openings leading into said corridor and sliding doors for the openings, pull bar means arranged for operator-controlled movement along one of said cell front walls to control the doors thereof, pull bar means arranged for movement along the other cell front wall to control the doors thereof, each of said pull bar means having a rack member, and means interassociating said rack members to cause the second pull bar to move with said operator-controlled pull bar, said interassociating means being located between said racks and not extending beyond either thereof. 70 75 80

2. In a jail structure having a pair of cell rows with a corridor therebetween, the front walls of said cells having door openings leading into said corridor and sliding doors for the openings, pull bar means arranged for operator-controlled movement along one of said cell front walls to control the doors thereof, pull bar means arranged for movement along the other cell front wall to control the doors thereof, each of said pull bar means having a rack member, and means interassociating said rack members to cause the second pull bar to move with said operator-controlled pull bar, said interassociating means including an endless means having a pair of bights bent about a pair of sprockets, each sprocket being positively associated with one of said racks. 90 95 100

3. In a jail structure having a pair of angularly related walls, said walls having door openings and sliding doors therefor, pull bar means for one of said doors arranged for operator-controlled movement, a rack member rigidly associated with said pull bar means, endless gap nut controlling means for the other door having a gap nut carrying stretch portion extending along the path of movement of the second door, rotary members at the ends of said stretch to locate bights in said endless means, one of said rotary members comprising a sprocket, the corresponding portion of said endless means comprising a chain bent thereabout, and gear means arranged to cause said sprocket to be driven by said rack. 105 110 115

4. In a jail structure having a pair of angularly related walls, said walls having door openings and sliding doors therefor, gap nut controlling pull bar means arranged for operator controlled movement parallel with that of one of said doors, a rack member rigidly associated with said pull bar means, endless gap nut controlling means for the other door having a gap nut carrying stretch portion extending along the path of movement of the second door, rotary members at the ends of said stretch to locate bights in said endless means, and rotary idler means interconnect- 120 125 130

ing said rack with one of said rotary members for positive drive therebetween, said endless means having positive driven connection with said last named rotary member.

5. In a jail structure having a pair of angularly related walls, said walls having door openings and sliding doors therefor, pull bar means for one of said doors arranged for operator-controlled movement, a rack member rigidly associated with said pull bar means, endless gap nut controlling means for the other door having a gap nut carrying stretch portion extending along the path of movement of the second door, rotary members at 15 the ends of said stretch to locate bights in said endless means, one of said rotary members comprising a sprocket, and the corresponding portion of said endless means comprising a chain bent thereabout, a gear rigidly associated with said sprocket, and gear means interconnecting said rack with said gear for positive drive therebetween.

6. In a jail structure having a pair of cell rows with a corridor therebetween, the front 25 walls of the cells of said rows having door openings leading into said corridor and sliding doors for the openings, a corridor wall extending across between said cell front walls and having an opening leading into said corridor and a sliding door for said opening, gap nut controlling pull bar means arranged for operator controlled movement along one of said cell front walls to control the doors thereof, gap nut controlling pull bar means 35 arranged for movement along the other cell front wall to control the doors thereof, each of said pull bar means having a rack member, endless gap nut controlling means for the corridor door having a gap nut carrying stretch 40 portion extending along the path of movement of the corridor door, sprocket members at the ends of said stretch to locate bights in said endless means, the corresponding portions of said endless means comprising chains 45 bent about said sprocket members, and gear means associating said sprocket members each with one of said racks.

7. In a jail structure having a pair of cell rows with a corridor therebetween, the front 50 walls of the cells of said rows having door openings leading into said corridor and sliding doors for the openings, a corridor wall extending across between said cell front walls and having an opening leading into said corridor and a sliding door for said opening, gap nut controlling pull bar means arranged for operator controlled movement along one of said cell front walls to control the doors thereof, gap nut controlling pull bar means 55 arranged for movement along the other cell front wall to control the doors thereof, each of said pull bar means having a rack member, endless gap nut controlling means for the corridor door having a gap nut carrying stretch portion extending along the path of 60 65

movement of the corridor door, sprocket members at the ends of said stretch to locate bights in said endless means, the corresponding portions of said endless means comprising chains bent about said sprocket members, and gear means associating said sprocket members, each with one of said racks, one of said gear means including an idler gearing for reversing the direction of drive, whereby the pull bars of said cell front walls will be 70 75 positively interconnected to move together.

In testimony whereof I hereby affix my signature.
